UNITED STATES PATENT OFFICE.

HENRY HESSELBACH, OF NEW YORK, N. Y., ASSIGNOR TO J. H. BUNNELL & COMPANY, INCORPORATED, A CORPORATION OF NEW YORK.

TELEGRAPH KEY.

Application filed May 1, 1926. Serial No. 105,981.

This invention relates to telegraph keys of the "high speed" type in which the key lever vibrates laterally, being shifted in one direction to form the dashes and being equipped with a spring reed for automatically producing a succession of dots, when shifted in the opposite direction.

These movements are effected by thrusting the thumb and forefinger in opposite directions against a vertically disposed flat finger piece at the end of the key lever. The speed and complexity of such movements have the effect of tiring and partially paralyzing the hand of the operator, sometimes with permanent ill effects.

The objects of this invention are to make it possible for the operator to shift the position of his hand and fingers from time to time, or at any time, to relieve fatigue and attain a more comfortable operating posture and to provide the structure for this purpose in a simple, inexpensive, easily adjusted and entirely practical form.

These objects are attained by certain novel features of construction, combination and relation of parts, one embodiment of which is illustrated in the accompanying drawing.

Figure 1 in the drawing referred to is a top plan view of a high speed telegraph key of approved construction having the invention incorporated therein.

Figure 2 is a side view of the key showing the finger piece lowered for operation by a flat wrist movement and indicating in broken lines how the same may be positioned at the usual horizontal level or at a higher angle.

Figure 3 is an enlarged broken detail view of the adjustable mounting for the finger piece.

The key shown being of a standard construction, needs no description other than to point out that it has a key lever 4 pivoted on a vertical axis at 5, with contacts 6 at one side of the same for making the dashes and contacts 7 at the opposite side for automatically producing dots by the vibration of the spring reed 8.

The finger piece by which the lever is vibrated is indicated at 9 in the form of a flat panel shaped to receive the impact of the thumb and forefinger on opposite sides and supported in vertical alinement at the back end of the key lever.

This finger piece is shown as set into the

edge of a supporting lug 10 and secured therein by rivets 11. The lug 10 is shown as having a centrally disposed reduced shank 12 at its forward end perforated at 13 for the free passage of a securing screw 14 and adapted to be held between the jaws 15, 16 at the end of the key lever. These jaws are shown as formed by cutting a wide slot 17 in the end of the key lever to receive the shank 12 of the finger piece and by cutting a narrower slot 18 inward from the wider slot to give the jaws a resilient quality. The spring jaws are preferably formed or set to exert a gripping pressure on the shank of the finger piece so that said finger piece will be yieldingly retained in any position to which it is adjusted even though the clamping screw be not set up tight. A screw seat 19 is shown formed in the jaw 16 and a free passage 20 for the screw in the other jaw 15, from which it will be seen, with the shank of the finger piece between the jaws, that upon tightening the screw by means of the operating head 21, the shank will be firmly clamped between the two jaws. Releasing the screw enables the finger piece to be shifted upward or downward and the removal of this one screw enables the finger piece being entirely detached.

The latter is an advantage when it is desired to pack the key for shipment or storage since the removal of this finger piece leaves the key with no parts projecting beyond the base. Greater compactness also is obtained by lowering the finger piece to the full line position shown in Figure 2 or below that, this reducing the overall dimensions so that the key may be packed in smaller space.

The structure disclosed enable the operator to instantly raise or lower the finger piece to suit his own particular preference. Tightening the clamp screw secures the finger piece in the desired adjustment and pressure on the finger piece in any direction has no effect upon the holding power of this clamp so that the finger piece will not work loose under continuous operation.

The spring gripping power of the jaws holds the finger piece in the position to which it is shifted, before the clamp screw is tightened. The placing of the clamp screw on the upper side of the key lever, as viewed in Figure 1, puts it in position where it may be operated by the fingers of the hand which op-

erate the key so that any changes of adjustment may be effected with the same hand which actuates the key.

In addition to other advantages mentioned, 5 the device is so simple, easily constructed and assembled that it adds but little to the present cost of the key. Also, the present key structures may be used, practically the 10 only modification of same necessary being to double slot the end of the key lever and provide in it, the passages 19, 20 for the clamp screw.

What is claimed is:

15 A telegraph key having a key lever vibrating on a vertical axis, said key lever having a vertical slot in the actuating end of the same providing spaced spring jaws, a horizontally disposed combined pivot and clamping screw having an actuating head 20 bearing against the outer face of one of said

spring jaws and a screw shank extending freely through said jaw and into engagement with the opposite jaw, whereby the same may be employed to force the jaws toward each other and a vertically disposed finger 25 piece having a shank portion entered between the spring jaws and perforated between said jaws for passage of the shank of the screw, whereby said finger piece is pivoted horizontally to the end of the key lever and is capable of arcuate adjustment in a vertical plane, being resiliently retained in such adjustments by the holding tension of the 30 spring jaws and fixedly secured in any of the positions of vertical adjustment by the 35 clamping action of the securing screw.

In witness whereof, I have hereunto set my hand this 28th day of April, 1926.

HENRY HESSELBACH.
